UNITED STATES PATENT OFFICE.

FREDERIC A. BARTGIS, OF FREDERICK, MARYLAND.

FENCE.

SPECIFICATION forming part of Letters Patent No. 314,419, dated March 24, 1885.

Application filed August 6, 1884. (No model.)

To all whom it may concern:

Be it known that I, FREDERIC A. BARTGIS, a citizen of the United States, residing at Frederick, in the county of Frederick and State of Maryland, have invented certain new and useful Improvements in Farm-Fences, of which the following is a specification, reference being had therein to the accompanying drawings.

10 My invention relates to certain improvements in fences, and is designed, objectively, to produce a simple, cheap, and easily-constructed fence, such as can be used in inclosing farm-lands and the like. Its simplicity 15 makes it far cheaper and much more easily built than the ordinary worm or straight rail fence, while, not being affected by changes of temperature, it is superior to the wire fence. These various objects and advantages will be 20 apparent from the following description, in which reference will be had to the annexed drawings, in which—

Figure 1 represents a perspective of a completed fence; Fig. 2, a section through the same, and Fig. 3 a detail of the wire lock-piece.

25 A designates fence-posts that are permanently secured by being set in the ground. These posts may be old or defective and comparatively useless for other constructions of 30 fences, but in this they answer the purpose as well as perfectly sound ones.

Instead of being all on one side of the rails, the posts may be arranged so as to be alternately on each side of the said rails. A supplementary post, B, is hung on the fixed post A by means of loops C, preferably made of stout wire and of a double elliptical shape. The wire is first formed into a long loop, D, 40 and then after a securing-twist continued in opposite directions and returned, forming the said ellipses, passed through the loop D, returned over its end, and the ends of the said wire connected and secured by a twist, as 45 shown at E. By this arrangement the cross-loop D is held firmly in position, and all slip of

the same obviated. These loops are generally arranged one near the bottom and one near the top of the posts, one of the ellipses passing around the fixed post and the other around the supplementary post. In building the fence, a stone or other object is placed under the supplementary post, so that the loops C will rest about in a horizontal position, as shown in Fig. 2. The rails F of the fence are then placed in position, overlapping between the fixed and supplementary posts, as shown. The rails all having been placed in position, the blocks or stones are knocked from under, and the weight of the rails forces the supplementary post 50 downward till the loops C cramp, and so firmly lock the fence against upward pressure such as might be brought to bear against it. The posts are so arranged as to permit the supplementary post to be somewhat above the ground 55 when the fence is locked. The construction of the loop is such as to stand all the strain brought to bear on it, and by embracing the posts permits the use of those of inferior quality, which adds greatly to the cheapness 60 of the said fence, while its utility and lasting qualities are fully maintained. By placing the lower loop about midway on the post the number of rails may be lessened, forming thereby a cheap fence for large animals. 65

I am aware that a double wire loop in the construction of fences is not new; hence I do not claim such a loop generally; but

What I do claim is—

70 A double loop constructed in the manner herein specifically described, in combination with a stationary post and an auxiliary post materially shorter than the stationary one, and the rails between said posts retained and secured in the manner herein described. 75

In testimony whereof I affix my signature in presence of two witnesses.

FREDERIC A. BARTGIS.
